UNITED STATES PATENT OFFICE.

NELSON C. DURAND, OF NEWARK, NEW JERSEY, ASSIGNOR, BY MESNE ASSIGNMENTS, TO THOMAS A. EDISON, INCORPORATED, OF WEST ORANGE, NEW JERSEY, A CORPORATION OF NEW JERSEY.

PHONOGRAPH.

Application filed August 17, 1923. Serial No. 657,918.

My invention relates to phonographs and more particularly to phonographs of the business or commercial type, and in some aspects is an improvement on the invention disclosed in Patent No. 1,297,466, granted March 18, 1919, to Newman H. Holland and entitled Speaking tube support for phonographs.

A phonograph of the business or commercial type is usually equipped with a speaking tube comprising a mouthpiece connected to the phonographic recorder by a convenient length of rubber or metallic flexible tubing. One of the objects of my invention is to provide in a phonograph an improved construction and arrangement comprising means preferably constituting a support for holding the speaking tube conveniently positioned when the latter is not in use, for operating or controlling the switch or other device which controls the operation of the driving or other movable mechanism of the phonograph.

Another object of my invention is to provide an arrangement wherein movement of the cover or top plate of the phonograph casing or cabinet to open position may be more conveniently and easily effected, preferably, by the means above described for operating the switch or other device which controls the movable phonograph mechanism.

Other objects and features of my invention will be hereinafter more fully described and claimed.

In order that my invention may be more clearly understood, attention is directed to the drawing accompanying and forming a part of this specification, and in which:

Figure 1 represents a perspective, fragmental view of a phonograph having a preferred embodiment of my invention applied thereto;

Figure 2 is an enlarged view in side elevation, partly broken away, of the phonograph shown in Fig. 1, with the cover or top plate in raised or open position; and

Figure 3 is a fragmental view similar to Fig. 2 showing the speaking tube support locked in position to maintain the switch in circuit-opening position.

Referring to the drawing, reference character 1 represents the cabinet or casing of a business or commercial phonograph of the

Edison type and 2, the cover of said cabinet, 55 constituting the top plate of the phonograph, which is hinged to the cabinet as indicated at 10. Extending upwardly from the cover or top plate 2 and preferably formed integrally therewith are suitable standards 2' 60 in which is rotatably mounted a pulley 3 and the axle of the mandrel or rotatable record support 4. As is common in the art, the pulley 3 is driven from an electric motor 6 or other suitable driving means, as by a belt 65 7, to thereby impart rotation to the mandrel 4 and the record tablet 5 mounted thereon. The motor 6 is suitably supported from the cover or top plate 2 within the cabinet 1, the circuit of this motor being controlled by a switch 8 having a reciprocatory contact member 9 suitably biased, as by a spring, to its raised position, as shown in Fig. 2, in which the switch is closed. It is thus apparent that the switch 8 is a "normally on" 70 75 switch. A plate 11 is suitably secured, as by means of screws, on the top of the cover 2, this plate being provided at its rear side with an upstanding bracket 12. Reference character 13 represents a support for the speaking tube of the phonograph, this support being in the form of an arm pivoted at its inner end to the bracket 12. The outer end portion of the support 13, which projects beyond the casing 1 and cover 2, is 80 85 curved as indicated at 14, to form a rest for the speaking tube and is preferably covered with a sheath 15 of soft rubber or other suitable material, which prevents the mouth-piece of the speaking tube from being scratched or marred by the support and which also tends to prevent the mouth-piece from slipping off the rest.

The arm 13 or support is so arranged that the under side thereof is engaged by the spring-pressed contact member 9, the weight of this arm being such that when the speaking tube is disengaged from the rest 14 thereof, said contact member will move upwardly to circuit-closing position and thereby move the arm upwardly about its pivot to the raised position shown in Fig. 2. The plate 11 is provided at its forward edge with an upstanding inverted U-shaped portion or yoke 18 which straddles the arm 13 and acts not only as a stop to limit the upward movement of the arm with respect to the cover 2 but as a guide for said arm 90 95 100 105

- 2 preventing any appreciable lateral move- top plate 2 to inspect the motor 6 or other
ment thereof. The speaking tube comprises parts disposed within the cabinet 1, or to
a trumpet-shaped mouth-piece 16 and a soft render such parts accessible for repair or
rubber or flexible metallic tubing 17, connected at one end to said mouth-piece and
5 replacement, this may be easily and conveniently accomplished by lifting upwardly on
at its other to the recorder (not shown). The weight of the mouth-piece 16 is such
the rest 14, or on that portion of support
10 about its pivot against the action of the spring-pressed contact 9, to its depressed
13 which projects outwardly beyond the cabinet 1, either when the member 19 is in
position as shown in Fig. 1. In this move- the position shown in Figs. 1 and 2 or in
ment of the arm 13 the contact member 9
15 will be forced downwardly against the action of its spring to circuit-opening position.
10 In order that the support 13 may be held
in its depressed position either when the
speaking tube is intentionally removed
20 from the rest 14 or accidentally displaced
therefrom a member 19 is slidably mounted
on the support 13 for adjustment to and
from a position beneath the base of the
yoke 18. This member 19 is in the form of
25 a button having a shank 20 which extends
through a slot 21 formed in support 13.
Mounted on the shank 20 between the bottom of the support 13 and a head 23 formed
on the lower end of the shank is a metallic
30 spring washer 22 which co-acts with the
support to frictionally hold the member 19
in any adjusted position. When the mem-
ber 19 is beneath the base of yoke 18 it co-
acts with the latter to hold or lock the sup-
35 port 13 and the contact member 9 in their
depressed positions.
In case the phonograph described is being
used at frequent intervals the member 19
40 is adjusted to a position in which it will
not engage the stop 18, that is to the position
shown in Fig. 2 in which the shank 20 thereof engages the outer end wall of
45 slot 21 in the arm 13. If the operator now
desires to dictate he removes the mouth-
piece 16 from the rest 14, whereupon the
50 spring of the spring-pressed contact mem-
ber 9 moves the latter and the support 13
upwardly to their raised positions. Such
movement of contact member 9 effects the
55 closing of the circuit of motor 6, which
through the belt 7 and pulley 3 will there-
upon impart rotary movement to the record
support 4. The operator then proceeds
60 with his dictation and upon the conclusion
thereof disposes the mouthpiece 16 on the
rest 14. The mouth-piece when so disposed,
moves the support 13 and contact member
65 9 downwardly against the action of the
spring of the contact member, to their de-
pressed positions, shown in Fig. 1, and
thereby effects the opening of the circuit
70 of motor 6. The motor 6 and the rotatable
record support 4 will thereupon come to
75 replacement, this may be easily and conveniently accomplished by lifting upwardly on
the rest 14, or on that portion of support
13 which projects outwardly beyond the cabinet 1, either when the member 19 is in
the position shown in Figs. 1 and 2 or in
locking position as shown in Fig. 3. It
will be obvious that upon so lifting up-
wardly on the support 13 either the latter
or the member 19, according to whether
such member is in the position shown in
Fig. 2 or in the position shown in Fig. 3,
will co-act with the base of the yoke 18 to
effect upward movement of the cover about
its hinge 10.
In case the phonograph is not to be used
80 for a considerable period the member 19
is moved to position beneath the yoke of 18
to thereby lock the support 13 and the con-
tact member 9 in their depressed positions,
as shown in Fig. 3. This insures the con-
tact member being held in circuit-opening
85 position so as to prevent operation of the
motor 6 with the consequent wastage of
current and wear of the parts, in the event
that the speaking tube is removed or acci-
90 dentally displaced from the rest 14.
While I have described a preferred em-
bodiment of my invention, it is to be under-
stood that the same is subject to numerous
95 changes and modifications without depar-
ture from the spirit of the invention or the
scope of the appended claims.
Having now described my invention,
what I claim as new and desire to protect
100 by Letters Patent, is as follows:
1. In a phonograph, driving mechanism,
means for controlling the operation of the
105 same, said means being movable to render
said driving mechanism operative and inop-
erative and being biased to a position to
render such mechanism operative, a support
110 for a speaking tube movable by the latter
when the same is applied thereto to a posi-
tion in which it is adapted to hold said con-
trolling means so positioned as to render
115 said driving mechanism inoperative, and
means comprising a member adjustable on
said support to lock the latter in such posi-
tion when the speaking tube is removed
therefrom, substantially as described.
2. In a phonograph, driving mechanism,
120 a cabinet having a movable cover, means
for controlling said driving mechanism
comprising a movable support for a speak-
ing tube, and guiding means for said sup-
port mounted on said cover, said guiding
125 means being arranged to limit the move-
ment of said support with respect to said
cover in one direction and to cooperate with
said support upon movement of the latter
130

ment of said cover, substantially as described.

3. In a phonograph, driving mechanism, a cabinet having a movable cover, means for controlling said driving mechanism comprising a support for a speaking tube mounted on said cover for pivotal movement, and a member mounted on said cover embracing said support, said member acting to limit the upward movement of said support about its pivot and cooperating therewith to effect opening movement of said cover upon such upward movement of the support, substantially as described.

15 4. In a phonograph, driving mechanism, means for controlling the operation of the same, a cabinet having a movable cover, a support for a speaking tube movably mounted on said cover and arranged to actuate said controlling means, a guide for said support having means limiting movement of said support with respect to the cover in one direction and cooperating with the support when the latter is moved in such direction to effect opening movement of said cover, substantially as described.

5. In a phonograph, a cabinet having a movable cover, phonograph mechanism carried by said cover, means movable to positions to render said mechanism operative and inoperative and biased to one of said positions, a support for a speaking tube movably mounted on said cover and adapted to effect movement of said means to the other of said positions, and a guide for said support mounted on said cover and having means limiting the movement of said support with respect to said cover in one direction and cooperating with said support when the same is moved in such direction to effect opening movement of said cover, substantially as described.

45 6. In a phonograph, a cabinet having a movable cover, a rotatable record support mounted on said cover, electric driving mechanism for said record support supported from said cover within said cabinet, a switch movable to positions to effect the opening and closing of the circuit of said mechanism, a support for a speaking tube movably mounted on said cover and arranged to control said switch, and a guide for said support mounted on said cover, said guide having means limiting the movement of said support with respect to the cover in one direction and adapted to cooperate with

the support when the latter is moved in such direction to effect opening movement of the cover, substantially as described.

7. In a phonograph, a cabinet having a hinged cover, movable phonograph mechanism, a switch for controlling said mechanism comprising a movable contact member biased to circuit-closing position, an arm pivotally mounted on said cover engaging but unattached to said contact member and normally held thereby in raised position, and a guide for said arm having means for limiting the upward movement of said arm with respect to said cover and adapted to cooperate with said arm when the latter is moved upwardly to effect opening movement of said cover, substantially as described.

15 8. In a phonograph, a cabinet having a hinged cover, movable phonograph mechanism, a switch for controlling said mechanism comprising a reciprocatory contact member biased to circuit-closing position, an arm pivotally mounted on said cover engaging said contact member and normally held thereby in raised position, a stop for limiting upward movement of said arm with respect to the cover, and a member adjustable on said arm to a position beneath said stop, said member when in said position co-acting with said stop to hold the arm in depressed position and thereby said contact member in circuit-opening position, substantially as described.

25 9. In a phonograph, a cabinet having a movable cover, electric motive mechanism, a switch for controlling the circuit of said mechanism comprising a movable contact member biased to circuit-closing position, an arm movably mounted on said cover and engaging said contact member, a stop for limiting movement of said arm in one direction with respect to the cover, said contact member tending to hold said arm against said stop, said stop adapted to cooperate with said arm when the latter is moved in one direction to effect opening movement of said cover, and a member adjustable on said arm to a position beneath said stop, said member when adjusted to said position being effective to hold said arm in depressed position and thereby said contact member in circuit-opening position, substantially as described.

This specification signed this 15th day of August, 1923.

NELSON C. DURAND.
